UNITED STATES PATENT OFFICE.

GUY HILL, OF WASHINGTON, DISTRICT OF COLUMBIA, ASSIGNOR, BY DIRECT AND MESNE ASSIGNMENTS, TO WIRED RADIO, INC., OF NEW YORK, N. Y., A CORPORATION OF DELAWARE.

SUPPORTING PLATE FOR ELECTRICAL CONDENSERS.

Application filed May 16, 1921. Serial No. 469,965.

This invention is a modified form of the construction disclosed in Patent No. 1,408,738.

This invention relates to an improved construction of insulation for the supporting plates of a condenser, and it is applicable either to a variable air condenser or to a fixed air condenser and the same principles also apply if oil is used instead of air between the plates and also if any other dielectric is used.

The invention is particularly valuable when applied to either fixed or variable condensers used in radio telegraph and radio telephone systems, although it is of value for other analogous work.

The main object of the invention is to construct an insulating supporting plate for a condenser having one or more metallic bushings molded into the plate.

Another object of the invention is to construct a novel insulating structure by means of which there may be molded into each of the supporting insulating discs a metallic plate which can serve as one of the fixed plates of the condenser. By this means the strength of the supporting plates will be increased mechanically and also considerable space will be eliminated so that a condenser of greater capacity can be constructed.

Another object of my invention is to provide such a structure to consist of but few parts, simple and inexpensive to manufacture.

Another object of my invention is to obviate the mechanical and electrical defects found in prior structures of this character.

Other objects will appear from the subjoined specification and claims.

Referring to the drawings:

Fig. 1 is a top view of one of the supporting plates of the condenser.

Fig. 2 is a section of the condenser on the line A—A of Fig. 1.

Fig. 3 is a section of the supporting plate shown in Fig. 1 on the line B—B of that figure.

Fig. 4 is a plan view of a portion of a supporting plate similar to Fig. 1, but showing a different form of bushing and insulating material adjacent to the bushing.

Fig. 5 is a plan view of another form of supporting plate.

Fig. 6 is a section on the line C—C of insulating plate shown in Fig. 5.

Fig. 7 is a plan view of a modified form of one of the condenser supporting plates embodying my invention.

Fig. 8 is a section on line D—D of Fig. 7.

While the illustrations and constructions shown in the drawings relate more particularly to a variable air condenser, as has been stated above the same principles apply to a fixed air condenser and likewise also apply if oil is used instead of air between the plates, and also when any other dielectric is used.

The structure illustrated is a simple form of variable air condenser with my invention embodied therein. It is therefore only necessary to generally describe the structure of the condenser in order to clearly understand the structure and efficacy of my invention.

Referring to Fig. 2, the condenser consists of the upper and lower fixed plates 1, which are the main supporting plates or discs, and they are held in place by metal clamping rods 6, which are here conventionally shown, but may be of any approved construction, the plates being secured to the rods by suitable nuts 7. 2' are the fixed metal plates in electrical contact with the metal rods 6. 10 are the movable plates in electrical contact with the shaft 8, and these fixed plates and movable plates are respectively separated on the supporting rods 6 and the shaft 8 by suitable spacers, as well understood in the art. A handle 9 is secured to the shaft 8 by means of which the shaft may be turned in bushing 5. Since the invention relates specifically to the details of the supporting plates 1, a detailed description of the construction of the condenser itself in which the supporting plates are to be used is not considered necessary, as it forms no part of this invention.

Each of the supporting insulating plates 1 has a fixed plate 2 secured thereto by molding them, in the event that the plate is made of moldable insulating material. I also provide bushings such as 21 and 22, as illustrated in Fig. 6 in an insulating supporting plate 20, or a combination of bushings 3, 4 and 5, as illustrated in Fig. 3, together with a metallic plate 2, also shown in Figs. 2 and 3, by molding the insulating

plate thereto during the process of manufacture.

The metallic bushings such as 3, 4 and 5 shown in Fig. 3 can be made flush with the insulating material or they can extend slightly above the material, as illustrated for instance in Fig. 4, in order that no strain will be put upon the insulating plate 1, when the supporting rods are clamped in place.

- 10 Fig. 4 illustrates another form of bushing which is of greater length than the thickness of the insulating plate proper as shown at 20 so that a longer bearing surface if desired can be obtained. The insulating material 15 adjacent to the bushing is shown corrugated in order that greater leakage surface insulation may be obtained, and the outer surface of the bushing is provided with means to effectually anchor the same to the plate.
- 20 Referring to Fig. 3 the bushing 5 is separated from the plate 2 by insulating material, as the bushing 5 is connected to the movable plates of the condenser, while the plate 2 as stated above forms one of the fixed 25 plates of the condenser. The metal bushing 4 is supported entirely in the insulating material, but the metal bushing 3, however, can be in electrical contact with the metallic plate 2 since the bushing 3 is in electrical 30 contact with the supporting rod 6 which holds all the fixed plates of the condensers and it would therefore be at the same polarity as the fixed plate 2 and fixed plate 2'.

As clearly illustrated in Figs. 7 and 8, I 35 may provide a supporting plate 1² substantially one half of which is made entirely of metal 2² and the other half 3² of solid insulating material as distinguished from the structure shown and described in Figs. 1, 2 40 and 3, in which the condenser plate is molded at one side and to one surface of the insulator plate.

The two parts 2² and 3² are secured together by the formation 35 between the ad-

joining edges of the metal on the one hand 45 and the insulation on the other, as clearly shown in the drawing.

In the construction of this device it is only necessary to provide holes 6² through the metal portion of the supporting plate for the 50 reception of three of the connecting rods 6 and a bushing 4² secured to the insulation by molding it thereto, as illustrated in Fig. 3. The bushing 30 is secured to the insulation at the center of the entire structure 55 by molding the same thereto in a manner above described with respect to the bushings 5 and 21.

As changes of construction could be made within the scope of my invention, it is intended that all matter contained in the above description or shown in the accompanying drawings shall be interpreted as illustrative and not in a limiting sense.

Having thus described my invention what 65 I claim as new and desire to secure by Letters Patent is:

1. A supporting plate of insulating material having a substantially semi-circular metallic plate secured thereto by a tongue 70 and groove joint in position to act as a plate of a variable condenser and having metallic bushings extending through the plate of insulating material and insulated from said metal plate and projecting slightly beyond 75 the face of said plate of insulating material.

2. A supporting plate of insulating material having a substantially semi-circular metallic plate secured thereto by a tongue and groove joint in position to act as a plate of a 80 variable condenser and having metallic bushings extending through the plate of insulating material and insulated from said metallic plate.

In witness whereof, I have hereunto set 85 my hand at Washington, District of Columbia, this 23d day of April, 1921.

GUY HILL.
